OR D 5,637

5,637

UNITED STATES PATENT OFFICE.

GASTON PROTIN, OF NEW YORK, N. Y., ASSIGNOR TO HECTOR SINCLAIR,
OF SAME PLACE.

DESIGN FOR CENTER ORNAMENT FOR CEILINGS.

Specification forming part of Design No. 5,637, dated March 5, 1872.

Specification describing a Center Ornament for Ceilings, invented by GASTON PROTIN, of the city, county, and State of New York.

The nature of this design is fully represented in the accompanying photograph, to which reference is made.

The body A of the ornament is of circular form, and it has at its center a boss, a. Radiating from this boss are four foliated figures, b b, interposed by others, c c. The figures b b are bounded by a corresponding number of arcs, d d, and the figures c c project between them. Projecting or radiating from opposite sides of the body of the ornament are two figures, e e, whose configuration is fully illustrated in the photograph, and radiating from it at intermediate points are other figures, f f, whose form is also fully shown. Between these figures

ures e and f are other figures g and h, the latter consisting of a vase of flowers, and the other of a vase of fruit.

What I claim as my invention is—

1. The design and configuration of the body A, substantially as described.
2. The design and configuration of the figure e, substantially as represented.
3. The design and configuration of the figure f, substantially as represented.
4. The design and configuration of the figure g, substantially as described.
5. The design and configuration of the figure h, substantially as described.

GASTON PROTIN.
